CHECK MEMBER FOR LAUNDRY CHECKING DEVICES

Filed June 15, 1927

Inventor:
John H. Todd

by George W. Gaywell
Attorney.

UNITED STATES PATENT OFFICE.

JOHN H. TODD, OF CLEVELAND, OHIO, ASSIGNOR TO THE KEY-TAG CHECKING SYSTEM COMPANY, OF CLEVELAND, OHIO, A CORPORATION OF OHIO.

CHECK MEMBER FOR LAUNDRY-CHECKING DEVICES.

Application filed June 15, 1927. Serial No. 198,921.

My invention relates to laundry-checking devices. Particularly, the invention relates to check members utilized for segregating into different classes or bundles the commingled laundry pieces or nets after the mass of laundry has been washed and it is desired to assemble together in respective bundles the laundry pieces which belong to different persons. More particularly, the invention relates to improvements of a character which will prevent the check members which are attached to the several pieces of laundry or nets or identifying waste pieces from being caught in the washing machines or tumblers or other laundry appliances in which the articles are treated. Various parts of these laundry machines, such as the wash wheels, tumblers, cradles, etc., are provided with doors or other elements which, for various reasons, occasionally open up to a degree or present cracks into which the check members, which are usually comparatively small substantially flat stamped plates, creep or become trapped, and, when the cause for the crack or other opening is eliminated, and the cracks close, these check members are firmly caught and, consequently, also the garment pieces or nets or identifying waste pieces which are attached to them; oftentimes to the great detriment of the garments, nets and to the check members, and always to the impairment of the laundry operation. Oftentimes this entrapment occurs as follows. The laundry machine comes to a position where its door or entry-closure is on the bottom, and the weight of the contained laundry and water forces the door somewhat open so as to furnish a crack into which the upper edge of the check members may creep. Then when the laundry machine is moved and the strain is somewhat removed from the door, the latter closes somewhat and the check members are securely trapped. Then subsequent operations are apt to result only in the more secure entrapment of the check members. It is usually the so-called upper edge of these check members which thus become trapped. Usually the laundry piece or net or identifying waste piece is secured to the bottom edge of the check member and thus this edge is quite effectually protected from entrapment. I therefore, preferably, provide my improved check member with means adjacent its upper edge which obviate the entrapment.

The annexed drawing and the following description set forth in detail certain means embodying my invention, the disclosed means, however, constituting but three of the various mechanical forms in which the principle of my invention may be applied.

In said annexed drawing:

Figures 1, 2 and 3, represent, respectively, a front elevation, a side view, and a plan of one form of my improved check member;

Figures 4, 5 and 6 represent, respectively, a front elevation, a side view, and a plan of a second form of my improved check member; and

Figures 7, 8 and 9 represent, respectively, a front elevation, a side view, and a plan of a third form of my improved check member.

Referring to the annexed drawing in which the same parts are indicated by the same respective ordinals in the several views, the body portion 1 of a check member is formed with a slot or opening 2 of a certain character and provided with a number 3. The numbers 3 alone would serve as segregating indicia by attaching check members all bearing the same number to the same class or bundle of laundry pieces. Oftentimes these numbers are displayed upon pins 6 which are secured to the several pieces of laundry or nets. However, as plainly pointed out in my Patents Nos. 1,343,423 and 1,399,906, of June 15, 1920, and December 13, 1921, respectively, mistakes in segregating the laundry often occur where numbers alone are depended upon as segregating indicia, so that preferably check members are used which are formed with slots of various characters adapted to co-operate with keys formed, respectively, with complementary splines or other means, whereby in the checking of the various pieces of laundry and verifying the reading of the numbers, if the latter are also used, only those pieces of laundry or nets are segregated into one bundle which have attached to them check members of a character adapted to co-operate with one certain key. This, then, is the form of check member shown in the accompanying drawing and in which have been incorporated my improved means for preventing the entrapment which has been described.

This check member body 1 is shown in the forms of device of Figures 1 and 4 as connected to the pin 6 by a loose ring 5; whereas, in a form of device shown in Figure

7, the pin 6 is directly loosely connected to the body member 1. The three forms of device shown in the accompanying drawing are provided, respectively, with three forms of 5 means for increasing the effective thickness of the edge of the body member 1 so as to reduce its liability of being trapped. As hereinbefore described, preferably this improvement is incorporated in the upper edge 4 of 10 the check member body 1.

In the form shown in Figures 1, 2 and 3, this improvement consists in passing a plurality of rings 7 at spaced areas through the body 1 and adjacent its upper edge 4, these 15 rings, in the form of device shown, being two in number and loosely connected to the body 1 at about the ends of its upper edge and being of a diameter larger than the thickness of the edge 4 and extending outwardly from 20 the body member 1, all as plainly shown in Figures 1, 2 and 3, wherein it will be noted, particularly in Figures 2 and 3, that the effective thickness of the upper edge 4 is thus made substantially four or five times the normal thickness of the edge. Thus a crack of 25 corresponding width would necessarily have to be created before such a check member could become caught and an opening of such dimensions would be practically unknown in 30 standard laundry machinery. The loose connection of the rings 7 affords a large effective area for their use, as plainly shown by dot-and-dash lines in Figure 1.

In the form of device shown in Figures 4, 35 5 and 6, the desired result is obtained by the use of rivets 8 passed through the body member 1, in the illustrative form of device shown, in about the same areas as the rings 7, and formed with enlarged or broken-over heads 9 40 which afford an effective edge thickness for the desired object of the character shown plainly in Figures 5 and 6.

In the form of device shown in Figures 7, 45 8 and 9, no extra element is added to the body member 1, but the upper edge 4 of the same is so formed during the stamping operation, or otherwise so formed, as to reversely bend the same to create the angles 10 and the curved side walls 11 to about the depth plainly shown 50 in Figure 8, whereby the effective thickness of the edge 4 itself, in so far as permitting the entry of the same into laundry machinery cracks is concerned, is substantially that shown in Figures 8 and 9.

55 In the above description I have referred to "identifying waste pieces". I will explain what is meant thereby. Oftentimes, the laundry of one individual will fill an entire tub or tumbler. There is then no necessity of marking every piece. So it is customary to attach a proper check member to any waste or extra piece of fabric and throw it into the tub with the laundry and this serves as an identifying check for the whole tub or cradle.

65 What I claim is:

1. A check-member for laundry-checking devices comprising a body portion adapted for attachment to the article to be treated in the laundry machine, and rings of a diameter greater than the thickness of the edge of said portion intersecting the latter at spaced areas and extending outwardly therefrom to reduce the liability of the entrapment of the outer edge of the check-member in the laundry machine. 75

2. A check-member for laundry-checking devices comprising a body portion formed to adapt the same for attachment at one side to the article to be treated in the laundry machine, and rings of a diameter greater than the thickness of the edge at the opposite side intersecting the latter at spaced areas adjacent its edge and extending outwardly therefrom. 80

3. A check-member for laundry-checking devices comprising a body portion formed to cooperate with a complementarily formed key and provided with means adapted for its attachment to the article to be treated in the laundry machine, and individual spaced 85 means secured adjacent the edge of the body portion for reducing the liability of the latter to being trapped in the laundry machine. 90

4. A check-member for laundry-checking devices comprising a body portion formed to cooperate with a complementarily formed key and provided with means adapted for its attachment to the article to be treated in the laundry machine, and rings of a diameter greater than the thickness of the edge of said portion intersecting the latter at spaced areas and extending outwardly therefrom. 100

5. A check-member for laundry-checking devices comprising a body portion formed to cooperate with a complementarily formed key 105 and provided with means adapted for its attachment at one side to the article to be treated in the laundry machine, and rings of a diameter greater than the thickness of the edge at the opposite side intersecting the latter at 110 spaced areas adjacent its edge and extending outwardly therefrom.

6. A check-member for laundry-checking devices comprising a substantially flat plate adapted for attachment adjacent its bottom edge to the article to be treated in the laundry machine, and formed with segregating indicia, and means increasing the effective thickness of its upper edge to reduce the liability of its being trapped in the laundry machine. 115

7. A check-member for laundry-checking devices comprising a substantially flat plate adapted for attachment adjacent its bottom edge to the article to be treated in the laundry machine, and formed with segregating indicia, and rings of a diameter greater than the thickness of its upper edge intersecting the latter at spaced areas and extending outwardly therefrom. 125

8. A check-member for laundry-checking 130

devices comprising a body portion adapted for attachment to the article to be treated in the laundry machine, and provided with individual spaced elements increasing the effective thickness of its edge to reduce the liability of its being trapped in the laundry machine.

9. A check-member for laundry-checking devices comprising a substantially flat plate adapted for attachment to the article to be treated in the laundry machine, and individual spaced elements secured thereto to increase the effective thickness of the plate edge

to reduce the liability of its being trapped in the laundry machine. ¹⁵

10. A check-member for laundry-checking devices comprising a body portion adapted for attachment to the article to be treated in the laundry machine, and provided with individual spaced elements loosely secured thereto adjacent its edge to reduce the liability of its being trapped in the laundry machine. ²⁰

Signed by me this 24th day of May, 1927.

JOHN H. TODD.
